UNITED STATES PATENT OFFICE.

DANIEL M. SOMERS, OF NEW YORK, N. Y.

PROCESS OF MAKING THIN PLATE.

No. 800,837.

Specification of Letters Patent.

Patented Oct. 3, 1905.

Application filed May 24, 1905. Serial No. 262,088.

To all whom it may concern:

Be it known that I, DANIEL M. SOMERS, a citizen of the United States, residing at New York, county of Kings, and State of New York, 5 have invented certain new and useful Improvements in Processes of Making Thin Plate, fully described and represented in the following specification and the accompanying drawings, forming a part of the same.

10 This invention relates to an improved process for making thin plate—such, for instance, as the plate which is used as the basis for commercial tin-plate.

15 In the ordinary operation of making thin plate of the character referred to as it is now carried on the plate is produced by subjecting plate-bars to the proper heating and rolling operations until the desired gage of plate is reached. The plate is then pickled, the sheets 20 subjected to the pickling process, ordinarily measuring about twenty by twenty-eight inches, the thickness varying according to the standard gage of plate to be produced. This pickling operation cleans the plate and removes the scale therefrom. After pickling 25 the plate is annealed and then cold-rolled to surface it. The plate is then ready for the tinning process if it is to be made into tin-plate or for other commercial uses.

30 The present invention has for its object to reduce the cost of producing thin plate of the general character referred to and at the same time to improve the character of the product.

In accordance with the invention the heating, 35 reducing, and such subsequent operations as may be necessary are carried on after pickling. In carrying out the invention sheets of pickled plate are subjected to heat in a furnace to raise them to a temperature to enable 40 them to be subjected to subsequent reducing and elongating operations. The sheets treated will vary in size and thickness according to the size and gage of plate to be finally produced. If, for instance, plate which is to 45 serve as a basis for commercial tin-plate is to be produced, the pickled plates referred to may conveniently be about twenty-eight by thirty-six inches and about one-sixteenth of an inch thick. These plates after being pickled are 50 heated in a suitable furnace and are then subjected to pressure, preferably by rolling them, by which they are reduced in thickness and elongated, the product thus produced being sheets fifteen feet long by twenty-eight 55 inches wide and about .0116 of an inch in thickness, this being the thickness of what is

known as one-hundred-pounds standard plate. These sheets may then be annealed.

When the process is to be carried out in what is regarded as the best mode, the heating and subsequent operations will be carried on without permitting the plate to be acted upon by the air, thus preventing the formation of scale and the discoloration of the plate—that is, the product of the process is 65

“gray plate” or what is commercially known as “white plate,” as distinguished from the “black plate,” which is the product of the ordinary heating and reducing operations, which black plate must be pickled to clean it and remove the scale therefrom. When the process is carried on in this way, very marked economies result over the ordinary commercial process. In the first place the amount of surface to be pickled is greatly reduced, thus largely 70 reducing the cost of this operation. In the specific case above referred to the reduction amounts to four-fifths. In the next place a superior product is produced. In pickling very thin plate—that is, the plate which has 75 been reduced to standard gage—the acid pickling solution attacks the plate unevenly and in some places actually perforates it, so that the pickled product varies in grade. In making tin-plate this pickled plate is cold-rolled, 80

which operation surfaces the plate and removes to a certain extent the imperfections produced by pickling. A large number of these imperfections are, however, of such a character that they cannot be eliminated and 85 cannot be detected until after the plate is tinned, so that a very considerable amount of what is known as “wasters” occurs in commercial tin-plate—that is, imperfect sheets which have to be rejected and sold at a low 90 price. In fact, some of these imperfections—as, for instance, in cases where the sheet is thinned along a line of some length, but not actually perforated—escape detection even after tinning and are discovered by the breaking of the metal when it is attempted to put the sheets to commercial use. By pickling the sheets when they are comparatively thick and then subjecting them to the heating and pressure operations to reduce and elongate 95 them the imperfections produced by pickling are, in the first place, not nearly so extensive and, in the second place, are to a great extent cured or removed by the subsequent operations.

100 It has been stated that when the process is carried out according to the best way the

pickled plate will be subjected to the various operations without permitting it to come in contact with the air. It may be further remarked that better and more economical results will be produced if the sheets of plate prior to heating and reducing are assembled in packs and if the sheets, whether assembled in packs or not, are after the final reducing operation annealed without being exposed to the air and without permitting them to be exposed to the air between the final reducing operation and the annealing operation.

While, as has been indicated, the best results will be effected when the steps of the process referred to are carried on without permitting the pickled plate to become exposed to the air during the operations referred to, fairly good results may be obtained where the pickled plate is heated and elongated while exposed to the air, this being particularly true where packs of plate are being operated upon. When the process is carried on in this manner, it will probably be necessary to pickle the outside sheets of the pack after elongation; but the inner sheets will in a large measure be free from discoloration and scale.

Where especially high-grade product is desired, the pickled plate may be subjected to cold-rolling prior to the heating and subsequent operations. This cold-rolling will surface the sheets, and the surface thus obtained will be preserved to a great extent during the subsequent operations.

While the improved process is not dependent upon any particular form of apparatus, the apparatus described in an application filed by me on March 28, 1904, and serially numbered 199,831 is a suitable one for carrying it into effect.

It will be obvious that the process described not only has the great advantage of enabling thin plate to be produced at a less cost than heretofore, but it has the further advantage of enabling a very superior article of plate to be produced.

While the improved process is particularly advantageous when used in the production of thin plate which is to be used as a basis for commercial tin-plate, it will of course be understood that the product of the process may be used for many other purposes.

What is claimed is—

1. The process of making thin plate which consists in heating previously - pickled plate and then subjecting it to pressure to elongate the plate and reduce its thickness, these oper-

ations being carried on without exposing the plate to the action of the air, whereby formation of scale is prevented. 60

2. The process of making thin plate which consists in assembling previously - pickled sheets of plate in a pack, heating the pack, and then subjecting it to pressure to elongate 65 the plate and reduce its thickness.

3. The process of making thin plate which consists in assembling previously - pickled sheets of plate in a pack, heating the pack and then subjecting it to pressure to elongate 70 and reduce the plate in thickness, the heating and pressure operations being carried on without exposing the plate to the action of the air.

4. The process of making thin plate which consists in cold - rolling previously - pickled 75 plate, then heating the plate, and then subjecting it to pressure to elongate the plate and reduce its thickness, the heating and pressure operations being carried on without exposing the plate to the action of the air. 80

5. The process of making thin plate which consists in cold-rolling sheets of previously-pickled plate, assembling the sheets in a pack, heating the pack, and then subjecting the pack to pressure to elongate the plate and re- 85 duce the thickness. 85

6. The process of making thin plate which consists in cold-rolling sheets of previously-pickled plate, assembling the sheets in a pack, heating the pack, and then subjecting the 90 pack to pressure to elongate the plate and reduce the thickness, the heating and pressure operations being carried on without exposing the plate to the action of the air.

7. The process of making thin plate which 95 consists in heating previously-pickled plate, then subjecting it to pressure to elongate the plate and reduce its thickness, and then annealing, these operations being carried on without exposing the plate to the action of the air. 100

8. The process of making thin plate which consists in heating previously - pickled plate, assembling the plate in a pack, subjecting the pack to pressure to elongate the plate and reduce its thickness, and then annealing, the heating, pressure and annealing operations being carried on without exposing the plate to the action of the air. 105

In testimony whereof I have hereunto set 110 my hand in the presence of two subscribing witnesses.

DANIEL M. SOMERS.
